LOOM FOR WEAVING PILE FABRICS.

No. 268,202.

Patented Nov. 28, 1882.

UNITED STATES PATENT OFFICE.

JOHN C. DUCKWORTH, OF NEW YORK, N. Y., ASSIGNOR TO E. S. HIGGINS & CO., OF SAME PLACE.

LOOM FOR WEAVING PILE FABRICS.

SPECIFICATION forming part of Letters Patent No. 268,202, dated November 28, 1882.

Application filed January 27, 1880.

To all whom it may concern:

Be it known that I, JOHN C. DUCKWORTH, of the city, county, and State of New York, have invented certain new and useful Improvements in Looms for Weaving Pile Fabrics, of which the following is a full, clear, and exact description, reference being had to the accompanying drawings, forming part of this specification.

10 This invention relates to what is known as the "wire-motion" in looms for weaving pile fabrics.

One part of the invention is more particularly applicable to that kind of wire-motion which is the subject of English patent of George and John Collier, dated April 2, 1862, and which has been quite extensively used in this country. This part of the invention consists in an improvement in the mechanism for giving the necessary motion to the carriage or carriages carrying the wire-inserting and wire-withdrawing devices, whereby the loom is rendered more compact, and the wire slide or carriage is caused to have a long "dwell" after 20 the insertion of the wires in the warp, and a longer time is obtained for the beating up of 25 the lay.

The invention further consists in improvements in the devices which support the heads 30 of the pile-wires after the wires have been inserted into the shed, and in the means of supporting the inner or movable end of the yielding or movable wire slide-bar, whereby injury 35 to the shuttle and wire-motion in case of the stoppage of the shuttle opposite to said supports is prevented.

The accompanying drawings illustrate the 40 application of the several improvements to a loom for weaving Brussels carpets; but only those parts necessary to illustrate the invention are represented.

Figure 1 is a front elevation of the loom. Fig. 2 is a right-hand side elevation of the same. Fig. 3 is a vertical section of the same, 45 taken in a direction parallel with the warp, in the line *x x* in Fig. 1. Fig. 4 is a front view, showing parts of the mechanism for operating the wire-motion which are hidden from view in the front elevation, Fig. 1. Fig. 5 is a plan 50 of the principal parts of the wire-motion. Fig.

6 is a side view of a portion of the wire-motion, which will be hereinafter explained. Fig. 7 is a front view of a rotary shaft, crank, and rock-shaft lever, and their connections for working the wire-motion. Fig. 8 exhibits an end view 55 of the lay and corresponding side view of the picker-stick, and of the above-mentioned shaft, crank, and rock-shaft and connections.

A A indicate the main framing of the loom, consisting of two side frames of ordinary construction, connected by the breast-beam *A*² and cross-beams in the usual way, and having provided within or on them bearings for the crank-shaft *C*, which works the lay *D*, and for the cam-shaft *M*. 60

F is the guide-rail of the wire-motion, consisting of a straight and rigid horizontal bar, of dovetail or other suitable transverse section, secured firmly to the framing of the loom, and having fitted to slide along it the slide or carriage *F'*, which carries the wire-withdrawing hook *f*, the said slide or carriage being connected by a rod, *h*², with and receiving its motion from the arm *H'* of a horizontal rock-shaft, *h*, which is arranged in bearings in an outer frame, *A'*, 70 secured to the right-hand side frame of the loom, and occupies a position at right angles to the lay crank-shaft *C* and parallel with the side frames, A A. 75

G is the flexible bar, on which works the 80 slide or carriage *G'*, which carries the wire-inserting nippers *g*. This bar, which is bolted to the rail *F*, is curved and made with a bow at one end, as shown in the plan view, Fig. 5, to give it the necessary elasticity in a backward and forward direction. The slide or carriage *G'* is connected to slide or carriage *F'* by a rod, *f'*, so that the latter slide or carriage imparts to the former one its motion along the bar *G*. 85

The parts of the wire-motion thus far described are substantially of well-known construction, and therefore need no further description. 90

The rock-shaft *h*, with its arm *H'*, before described, and its arm *H*², (best shown in Figs. 1 and 8) constitute a lever, which occupies substantially the position of the lever heretofore used to operate the wire-inserting and wire-withdrawing devices, only its fulcrum is placed 95

lower down and farther from the main frame of the loom; and the said lever derives its motion from a crank, I' , on a rotary shaft, I , (see Figs. 1 and 2,) which is arranged at right angles to the lay crank-shaft C and parallel with and outside of the right-hand side frame, A , in bearings in the outer frame, A' . This shaft derives motion from the main crank-shaft C , at the rate of one revolution of shaft I to two of shaft C , through bevel-gears $C^2 I^2$, the said crank I' being connected by an adjustable shackle-rod, h' , with the arm H^2 of the rock-shaft lever. This crank-shaft I is substantially like that heretofore used, and is driven in the same way; but instead of being, as has been usual, arranged outside of the fulcrum or rock-shaft of the lever $h' H' H^2$ —that is to say, farther from the main frame of the loom than the said fulcrum, or else almost directly over said fulcrum—it is arranged at a considerable distance inside of it, or nearer to the said frame, in bearings in the outer frame, A' ; and instead of its front end, to which the crank I is attached, being extended forward to or nearly to the front of the loom, that end is so far in rear of the center of oscillation of the lay that the arm H^2 of the rock-shaft lever is enabled to be set so far back on its rock-shaft h that the picker-sticks D' may work in front of it. By thus keeping back the front end of the shaft I and the arm H^2 the said shaft is enabled to be brought very near the main or side frame, A , of the loom, where it can be better supported and occupies a good position; and the necessity of extending the lay crank-shaft C far beyond the main framing to enable the shaft I to be geared with it is obviated. The arrangement of the crank-shaft I between the side frame, A , and the fulcrum of the rock-shaft lever $h' H' H^2$, or inside the fulcrum of said rock-shaft lever, produces a motion of the wire slide or carriage different from that which it would have if the crank-shaft were arranged on the outer side of the fulcrum of said rock-shaft lever, or at a greater distance from the side frame. This motion is illustrated by Fig. 7, where the position of the parts represented in full outline is that when the wire is withdrawn, and the position shown in dotted outline is that when the insertion is completed. The crank I' will of course give to the arm H^2 a comparative dwell at the end of each movement; but this dwell will be longer when the wire is fully inserted than when it is completely withdrawn, because when the crank reaches the position shown in dotted outline the point of connection between the rod h' and the arm H^2 is very nearly on the center of the shaft I , and during the movement of the crank from the dotted position to that indicated by the line I'^* the wire remains stationary, or nearly so, while when the arm H^2 is at the position shown in full lines and the wire is withdrawn the point of connection between the rod h' and the arm H^2 is at its greatest distance from the shaft I , and the arm will be given but a short dwell. The wire is inserted while the crank I' moves

from the position shown in full outline to that shown in dotted outline. The wire-carriages then remain stationary, or nearly so, while the crank moves from the dotted position to the line I'^* long enough to permit the lay to give a double beat, if desired, and are withdrawn slowly, or while the crank is making a full half-revolution, which is advantageous, not only if the pile is to be cut, but because it always requires more power to withdraw the wire than to insert it. This desirable movement of the wire slides or carriages could not be attained if the shaft I were placed on the outer side of the fulcrum of the rock-shaft lever $h' H' H^2$, because the action would be reversed—that is, the point of connection between the rod h' and arm H^2 would be near to the center of the shaft while the wire was withdrawn, thus producing a long dwell, while the shorter dwell would take place when the wire was inserted, and when it would be objectionable.

It will be obvious that the above-described improvement for operating the slides or sliding carriages $F' G'$ would be equally applicable to a single slide or carriage carrying both the wire-inserting and wire-withdrawing devices, as the operation of the two carriages described is transmitted from carriage F' to carriage G' by a simple connection between them, which causes them to move together.

L (see Figs. 1, 2, 3, and 5) is the forked lever by which the points of the withdrawn pile-wires are carried back preparatory to being inserted into the shed. The said lever, having its fulcrum at l , Fig. 2, is operated by a cam, L^2 , Fig. 4, on the cam-shaft M acting on a lever, L^3 , which works on a fulcrum-pin, l' , and is connected with the lever L by means of a rod, l^2 . The cam acts to throw back the lever L for carrying back the wires, and the said lever is retracted by a spring, l^3 .

P (best shown in Figs. 2, 3, and 5) is the supporting-bar, which supports the heads of the pile-wires after the said wires have been inserted into the shed. This bar is pivoted loosely at its front end by a pivot, p , to the breast-beam, or to a small stand, p' , secured to the breast-beam of the loom, and it extends backward over the lay and beyond the rear-most position of the back thereof through a vertically-slotted or forked bracket, p^2 , which is secured behind the lay to the side framing, A , having in its normal condition its rear end supported on the bottom of the slot or fork in said bracket, and being prevented by the sides of the said slot or fork from moving laterally, while it is free to move upward when necessary. The said bar is curved at about the middle of its length, and its rear portion is so much elevated, as shown in Figs. 2 and 3, that the shuttles may pass under it without touching it in their ordinary movement along the raceway. In case of a shuttle stopping opposite to the said bar, and by the forward movement of the lay being caused to come in contact with the under side of the said bar, the

shuttle will lift the said bar, thereby avoiding the injury to the shuttle or wire-motion, which has been liable to occur in such case when the bar has been of the usual construction and rigidly attached to breast-beam in the usual way.

Q (best shown in Figs. 3, 5, and 6) is the bar for supporting the inner and movable end of the flexible or movable bar G, on which works the slide G', which carries the inserting-nippers. This bar is arranged over the bar P. Its rear end is turned upward, as shown at q, to serve as a back-stop to the bar G, and its front end is pivoted to the stand p' by a pin, q', and is held up to a proper position to support the said bar G, as shown in Fig. 6, by means of a fixed supporting pin or projection, q², secured in or provided on the standard p'. This pivoting of the bar Q allows it to be lifted up as far as necessary by the wire-head-supporting bar P and the superincumbent wire heads whenever the latter bar is raised by the shuttle, as hereinbefore described.

The take-up mechanism and the devices for operating the cumber-board of the Jacquard machine are not claimed as parts of this invention, the take-up mechanism being the subject of an application for patent filed by the present applicant July 2, 1880, Serial No. 12,894, and the devices for operating the cumber-board being the subject of his application, Serial No. 12,895, filed July 2, 1880.

What I claim as my invention is—

1. The combination, with the main framing and the carriage or carriages provided with the wire-inserting and wire-withdrawing mechanism, of a lever placed outside the main framing, working transversely thereto, and connected with said carriage or carriages, a rotary shaft occupying a position parallel with and out 35 side of said main framing, nearer thereto than the fulcrum of said lever, a crank upon said rotary shaft, means for imparting rotary motion to said shaft, and a rod connecting said lever with said crank, the whole arranged substantially 40 as herein represented and described.

2. The combination, with the carriage or carriages provided with the wire-inserting and wire-withdrawing mechanism, the lay, and the picker-sticks, of the rotary shaft I and its crank I', means for operating said shaft, the rock-shaft h, having an arm, H', connected with said carriage or carriages, and an arm, H², connected with said crank, the said arm H² and the crank and their connections being arranged in rear of the center of motion of the lay and in rear of the picker-sticks, all substantially as and for the purpose herein set forth.

3. The combination, with the lay and breast-beam, of a pile-wire-head-supporting bar, P, having a pivoted connection with the breast-beam, and extended rearward over the lay beyond the rearward position of the latter, and elevated to permit the shuttle to pass under it, substantially as and for the purpose herein described.

4. The combination, with the lay and breast-beam and a pile-wire-head-supporting bar, having a pivoted connection with the breast-beam and extending backward beyond the lay, of a fixed vertically slotted or forked supporting-bracket arranged behind the lay and receiving the rear part of said bar, substantially as herein described.

5. The combination, with the breast-beam, the pile-wire-head-supporting bar, having a pivoted connection therewith, and the flexible or yielding wire slide-bar, on which works the carriage which carries the wire-inserting device, of a supporting-bar which supports the movable end of the said wire slide-bar, and which has a pivoted connection with the breast-beam, substantially as herein described.

J. C. DUCKWORTH.
